(57) **CLAIM**

The ornamental design for a speaker transducer, as shown and described.

DESCRIPTION

FIG. 1 is a perspective view of a speaker transducer portion in accordance with an embodiment of my new design;

FIG. 2 is a top plan view thereof;

FIG. 3 is a front elevational view thereof, the rear elevational view being a mirror image;

FIG. 4 is a side elevational view of one side thereof, the opposite side elevational view being a mirror image;

FIG. 5 is a bottom plan view thereof;

FIG. 6 is an enlarged cross-sectional view of a portion thereof, taken along 6—6 in FIG. 2; and,

FIG. 7 is an enlarged cross-sectional view of a portion thereof, taken along 7—7 in FIG. 2.

The broken line showings of the circle in the central area of the transducer, and the horizontal lines in FIG. 3 are for illustrative purposes only and forms no part of the claimed design.
